CLAIM

The ornamental design for an explosion-proof box for electrical components, as shown and described.

DESCRIPTION

FIG. 1 is a front elevational view of the explosion-proof box for electrical components showing my new design;
FIG. 2 is a rear elevational view thereof;
FIG. 3 is a top plan view thereof;
FIG. 4 is a left-side elevational view thereof;
FIG. 5 is a right-side elevational view thereof; and
FIG. 6 is a bottom plan view thereof.
